UNITED STATES PATENT OFFICE.

CAMPBELL RIVERS, OF ST. LOUIS, MISSOURI.

STEP-LADDER.

SPECIFICATION forming part of Letters Patent No. 663,042, dated December 4, 1900.

Application filed November 28, 1899. Serial No. 738,546. (No model.)

To all whom it may concern:

Be it known that I, CAMPBELL RIVERS, a citizen of the United States, residing at St. Louis, in the State of Missouri, have invented 5 certain new and useful Improvements in Step-Ladders; and I do hereby declare the following to be a full, clear, and exact description of the invention, such as will enable others skilled in the art to which it appertains to 10 make and use the same.

My invention relates to improvements in step-ladders; and it consists in the novel combination and arrangement of parts, as will be hereinafter more particularly described and 15 claimed.

My invention consists in a ladder comprising side members, castings secured to said ladder and provided with pockets, extensions forming parts of said castings, lugs forming 20 parts of said extensions and arranged at right angles to the latter and adapted to coöperate with the side members of the ladder, fastening devices passed through said lugs and into the edges of the side members, said pockets 25 having opposite inclined flat-bearing surfaces, legs or supports located in said pockets and having upper flat ends, the edges of said legs adapted to coöperate with the bearing-surfaces of said pockets and on each side 30 a single bolt passing through one of said castings, the upper end of one of the legs proper, and a side member of the ladder, all of which will appear from the detail description to follow.

35 In the drawings, Figure 1 is a front elevation of my complete invention. Fig. 2 is a side elevation of the same. Fig. 3 is an enlarged detail and side elevation showing the hinge, and Fig. 4 is a cross-section taken on 40 the line $x x$ of Fig. 2.

Referring to the drawings, 1 represents the ladder proper, which is constructed in the usual manner and provided with steps 2, which are located between and secured to the 45 side members 3 of said ladder and projecting forward and beyond the latter. Secured to the outside surfaces of said members 3 on a line with the steps 2 are angular plates 4, which extend over the front edges of said side 50 members, having their free ends secured to the front inclined edges of the steps 2, nails

5 or other suitable fastening devices being employed to fasten the several parts together.

The hinge which I employ for the ladder or to movably connect the legs or supports 6 to the ladder proper consists of two castings 7, one of which is located on either side of the ladder proper and attached thereto by screws, nails, or other fastening devices, each of said castings being composed of a bracket having 60 an upper flat surface 8, upon which are adapted to rest the tops 9 or supporting member of the ladder, the opposite edges of the latter being in contact with the opposite lugs 10 of the castings 7, nails 11 being passed through 65 said lugs and into the opposite edges of the supporting bed or member 9, whereby the latter is securely fastened to the casting. The lower portion of the casting comprises a pocket 12, having opposite inclined flat bearing surfaces 13 and 14, said pocket receiving the upper end of one of the legs or supports 6, with one of its edges in contact with one of the inclined bearing-surfaces of said pocket. In other words, when the ladder is in an open 75 position one of the flat edges of the legs or supports will be in contact with the inclined bearing-surfaces 14 of the pockets; but when said ladder is in a closed position the opposite edges of said legs or supports will be in 80 contact with the inclined bearing-surfaces 13 of said pocket, whereby a perfect support and brace is given the legs 6 when in either position.

In order to secure the upper ends of the legs 85 to the casting 7 and in their proper position within the pockets 12 of the same, bolts 15 are passed through said castings, upper ends of the legs, and through the upper ends of the members 3 of the ladder proper, whereby the 90 said legs or supports may be freely moved in either direction.

Forming a continuation of the casting 7 and located below the flat surfaces 8 of the same is an arm or extension 16, having a lug 95 17 formed at right angles to the same, the extension and lug adapted to embrace the outer surface of the side members 3 and the front edges thereof, respectively, nails 18 or other fastening devices being passed through said 100 lug and into the edge of the members 3, whereby the castings 7 operate to securely

hold the ladder proper in a rigid position in respect to the castings.

By the employment of the pockets 12, or more properly the construction of the same, 5 I am enabled to cut the upper ends of the legs 6 square, as clearly shown in Fig. 3, which is not only a cheap construction in its manufacture, but a considerable amount of material is left which prevents the wood from 10 splitting as heretofore where it was necessary to cut off the corners of the upper ends of the legs in order to allow the latter to be turned within the pockets, whereby it will readily be seen that I not only construct a 15 cheaper ladder, but one that is more durable and lasting.

Having fully described my invention, what I claim is—

1. A ladder, comprising side members, castings secured to said ladder and provided with pockets, the latter having opposite inclined flat bearing-surfaces, legs or supports located in said pockets, and having upper flat ends, the edges of said legs adapted to coöperate 20 with the bearing-surfaces of said pockets, and 25 on each side a single bolt passing through one of said castings, the upper end of one of the

legs proper, and a side member of the latter, as and for the purpose described.

2. A ladder, comprising side members, castings secured to said ladder and provided with pockets, extensions forming parts of said castings, lugs forming parts of said extensions and arranged at right angles to the latter, and adapted to coöperate with the side members of the ladder, fastening devices passed through said lugs and into the edges of the side members, said pockets having opposite inclined flat bearing-surfaces, legs or supports located in said pockets, and having upper flat ends, the edges of said legs adapted to coöperate with the bearing-surfaces of said pockets, and on each side a single bolt passing through one of said castings, the upper end of one of the legs proper, and a side member of the ladder, as and for the purpose described. 30 35 40 45

In testimony whereof I affix my signature in presence of two witnesses.

CAMPBELL RIVERS.
